UNITED STATES PATENT OFFICE.

ABRAHAM LEVI, OF BALTIMORE, MARYLAND, ASSIGNOR OF ONE-HALF TO
MAX LEVI, OF BALTIMORE, MARYLAND.

SHIRT-WAIST.

SPECIFICATION forming part of Letters Patent No. 724,301, dated March 31, 1903.

Application filed December 31, 1902. Serial No. 137,271. (No model.)

To all whom it may concern:

Be it known that I, ABRAHAM LEVI, a citizen of the United States, residing at Baltimore, State of Maryland, have invented certain new 5 and useful Improvements in Shirt-Waists, of which the following is a specification.

This invention relates to improvements in shirt-waists, and has for its object to reinforce the waist about the waistband where the buttons are secured for holding the trousers.

Shirt-waists are in a large percentage of instances made of light material having an exterior band stitched thereto, and the buttons for holding the trousers are usually secured to said exterior band and the material of the waist. While this construction adds considerably to the strength of the garment about the waistband, it is not satisfactory, and the garments tear and the buttons pull 20 out.

The object, therefore, of this invention is to provide a reinforce construction about the waistband which will strengthen the garment and prevent tearing and the pulling out of 25 buttons.

The invention is illustrated in the accompanying drawings, Figure 1 illustrating a perspective view of a shirt-waist having a waistband of my improved construction; Fig. 2, 30 an enlarged sectional view of a portion of the waist material and reinforcing-bands; Fig. 3, an enlarged detail view of the inner band, and Fig. 4 an enlarged vertical section through the inner and outer bands and waist material.

35 In the drawings, A designates a conventional shirt-waist, the body, sleeve, and collar portions of which may be of any suitable style or construction. Secured to the body of the waist on the exterior thereof and near the 40 lower edge is a band a, preferably made of the same material as the waist, and on the interior the body portion of said waist is provided with a band b of some suitable coarse and strong fabric. The band b on the interior is wider than the band a on the exterior, and the two bands are secured together by 45 two rows of stitches c, which extend along the edges of the smaller exterior band, through the material of the waist, and then through 50 the wider interior band.

Buttons d for engagement with the trousers

are secured to the waist in the present instance by rivets d', which latter are provided on their inner ends with heads d'', which take against the interior band. When the trousers 55 are secured to the buttons, the strain on the latter tends to pull the buttons out, and this strain draws the rivet-heads d'' against the interior band b, so that the strain or pull on the buttons is resisted entirely by the interior band of coarse material. The outer band, therefore, is entirely relieved of strain.

It has been stated that the interior band is wider than the exterior band, also that the interior band relieves the exterior band of 65 the strain or pull on the buttons, and, further, that the stitching through the outer band is close to the edge of the latter.

When stitching the bands together through the waist material, the stitches c must be 70 made close to the edges a' of the exterior band, so as to prevent the formation of a fold or plait along the edge of the band on the exterior of the shirt-waist. Now if the inner band were made the same width as the 75 outer band the rows of stitches c would also extend in a parallel direction close to the edge of the inner band, and as the strain on the buttons is resisted entirely by the latter band the stitches, being close to the edges, 80 would be liable to pull through the material. Therefore by making the inner band wider than the outer band the stitches c through the inner band are made away from the edges and have a permanent hold on the material of the inner band, thus leaving a marginal edge e along the fabric outside of the 85 stitches.

It is obvious that the buttons may be of a detachable construction, so that they may be 90 removed when the waist is put in the laundry.

I am aware that heretofore it has been proposed to provide a shirt-waist with a detachable inner band of strong fabric, to which the buttons are secured, and to provide the 95 outer band with a series of buttonholes or slots for the buttons on the inner band to project through. This construction, however, fails to overcome the trouble, as the strain comes on the buttonholes and the latter give 100 away and tear. By the present invention, the waist being provided with an exterior

band and a reinforce interior band, both of which are stitched together through the waist material, and the buttons being secured to the interior reinforce-band, the strain and pull on the buttons are resisted entirely by said reinforce-band, which makes a strong and durable waist.

Having thus fully described my invention, what I claim as new, and desire to secure by Letters Patent, is—

A garment having two permanent waistbands, one on the exterior and the other on

the interior, the interior band being wider than the exterior band and both of said bands being secured together through the garment fabric by stitches, said stitches passing along the edges of the exterior band but spaced from the edge of the interior band. 15

In testimony whereof I affix my signature in the presence of two witnesses.

ABRAHAM LEVI.
